UNITED STATES PATENT OFFICE.

VERONICA CONSTANCE HUSSEY, OF NASHVILLE, TENNESSEE.

DESIGN FOR A DOLL.

Application filed July 15, 1922. Serial No. 3,095. Term of patent 3½ years.

To all whom it may concern:

Be it known that I, VERONICA CONSTANCE HUSSEY, a citizen of the United States, residing at 1901 Boscobel Street, Nashville, Tennessee, have invented a new, original, and ornamental Design for a Doll, of which the following is a specification, reference being had to the accompanying drawing, forming part thereof.

Fig. 1 is a face view of a doll showing my new design; and

Fig. 2 is a side view of the same.

I claim:

The ornamental design for a doll as shown.

In testimony whereof I hereunto affix my signature.

VERONICA CONSTANCE HUSSEY.
